ELUTRIATOR FOR HYDROCARBON CONVERSION SYSTEMS

Reyner Kollgaard, Media, Pa., assignor to Houdry Process Corporation, Wilmington, Del., a corporation of Delaware

Application April 30, 1952, Serial No. 285,269

12 Claims. (Cl. 209—20)

1

This invention relates to a method and apparatus for elutriating granular contact material for the removal of small-size particles, particularly as applied to the circulatory system of a catalytic hydrocarbon conversion unit.

The invention is particularly adapted for use in a hydrocarbon conversion system involving the continuous circulation of granular contact material having a particle-size in the order of about 1-15, and preferably 2-8, millimeters in diameter, which circulatory system includes a down-flow path through which the contact material gravitates as a compact moving mass, and an up-flow path through which the contact material is pneumatically elevated for return to the upper end of the down-flow path.

A typical system to which the present invention may be applied is disclosed in an article entitled "Houdriflow: New Design in Catalytic Cracking," appearing at page 78 of the January 13, 1949, issue of the "Oil and Gas Journal." The pneumatic lift disclosed in the article comprises an elongated vertical lift pipe having its lower inlet end portion extending into a lower lift hopper or engager, wherein contact material withdrawn from the lowermost contact zone of the down-flow path is engaged by one or more streams of lift gas and conveyed into and then upwardly through the lift pipe to an upper lift hopper or disengager containing the upper end portion of the lift pipe. Within the disengager vessel, the contact material discharged from the upper end of the lift pipe is separated from the accompanying lift gas by gravitational deceleration and free fall of the particles of contact material. The disengaged contact material gravitates to the lower region of the lift disengager, from which region it is continuously withdrawn and returned to the upper end of the down-flow path. The lift gas, substantially free of contact material, is separately removed and is passed to conventional means, such as a cyclone separator, for the usual removal of entrained fines.

It is a common practice in such systems to continuously by-pass a portion of the circulating contact material to an elutriator for the purpose of removing fines from the system, the fines being considered those particles which are about 14 mesh or smaller in size. The larger-size particles, which are suitable for reuse, are then returned to the circulatory system at any one of several points in the circulatory path suitable for the reintroduction of the contact material.

Heretofore, it has been a practice to withdraw the elutriator feed stream from the circulatory

2

system at some convenient location along its path of travel between the disengager and the point of introduction of the contact material into the hydrocarbon conversion unit. After the removal of undesired small-size particles, the contact material is returned to the circulatory system at some convenient lower level, such as directly into the lift engager.

In accordance with the present invention, the stream of contact material discharging upwardly into the lift disengager is intercepted during its free fall by tray-like members deposited at a plurality of levels within the disengager vessel. The contact material collected on the trays is passed stagewise downwardly from tray to tray in a plurality of separate circumferentially-spaced streams adjacent to the inner wall of the disengager, each having a relatively short distance of free fall. From the lowermost tray, the contact material gravitates freely to the lower region of the disengager vessel, from which region it is continuously withdrawn and passed downwardly to the uppermost zone along the down-flow path of the hydrocarbon conversion unit. A portion of the disengaged contact material is withdrawn from a location on one or more of the trays of the disengager at which there is a relatively high concentration of the smaller-size particles of disengaged contact material and is passed by gravity flow to an elutriator for the removal of undesirable small-size particles.

In a preferred embodiment of the invention the elutriator is so located that the separated large-size particles may be passed by gravity flow to the continuous compact moving mass of contact material gravitating through the down-flow path of the conversion unit. A portion of the lift gas separated from the contact material within the disengager is passed into the elutriator to effect in known manner therein the desired separation of fines from the large-size particles of contact material. The remaining portion of the disengager gas and the gas discharge stream from the elutriator are both passed to a common cyclone separator which removes the fines from the lift gas and the elutriator gas streams before passing the same to the stack.

In a multiple lift system employing a plurality of separate disengagers, each serving one or more lift pipes, the elutriator may receive its by-pass stream of contact material from one or from any number of the disengagers.

In a system where the disengager receives contact material withdrawn from a first lower kiln and the disengaged contact material is then

passed to a second upper kiln, as disclosed in my application, Serial No. 285,270, filed April 30, 1952, the elutriator vessel and the common cyclone serving the elutriator and the disengagers may conveniently be located one above the other axially over the upper kiln.

For a fuller understanding of the invention reference may be had to the following description and claims taken in connection with the accompanying drawings forming a part of this application, in which:

Figure 1 is a sectional view, in elevation, showing one embodiment of the invention as applied to a multiple lift system;

Figure 2 is a fragmentary sectional view, in elevation, showing the elongated downcomers at one side of the disengager vessel;

Figure 3 is a horizontal section taken along the line 3—3 of Fig. 1;

Figure 4 is a horizontal section taken along the line 4—4 of Fig. 1;

Figure 5 is a horizontal section taken along the line 5—5 of Fig. 1;

Figure 6 is a horizontal section taken along the line 6—6 of Fig. 1;

Figure 7 is an elevational view of the disengager vessel, with a portion broken away to show an embodiment of the invention wherein the elutriator is located internally of the disengager vessel;

Figure 8 is a horizontal section taken along the line 8—8 of Fig. 7;

Figure 9 is a horizontal section taken along the line 9—9 of Fig. 7; and

Figure 10 is an elevational view showing the elutriator applied to a disengager which does not have a storage or surge capacity in its lower region, the elutriator being positioned axially above and in open communication with the uppermost zone containing the downwardly moving compact column of contact material.

Referring to the embodiment of the invention illustrated in Figs. 1-6, the numeral 11 refers to the disengager vessel of a multiple pneumatic lift. The disengager is supported at the upper end of a pair of parallel lift pipes 12, and comprises an upper cylindrical portion 13 and a lower conical portion 14 eccentrically attached along its base to the lower perimeter of the cylindrical portion.

The upper end portions of the lift pipes pass through the sloping side of the eccentric conical portion 14 and terminate approximately at the level of the juncture between portions 13 and 14. The height of the conical portion and the discharge level of the lift pipes are such as to provide sufficient space in the bottom of the disengager for maintaining a compact moving bed 15 of disengaged contact material as surge capacity for the circulatory system. The axes of the lift pipes 12 are parallel to the axis of cylindrical portion 13, and are equally spaced therefrom on a common diameter.

At the lower end of the disengager, the apex of the conical portion 14 is connected to an inclined conduit 16 through which disengaged contact material from bed 15 may be continuously passed in the form of a compact moving column to the uppermost contact zone along the downflow path of the conversion unit, such as the reactor, not shown.

Within the disengager 11 the streams of contact material and lift gas discharging from the lift pipes 12 expand and merge in the upper region of the disengager. The approximate en-

velope of the merging and combined streams being shown by broken lines in Fig. 1.

Within the cylindrical portion of the disengager a series of vertically-spaced pairs of segmental trays 17—17', 18—18', 19—19', and 20—20' are attached to the vessel walls at opposite ends of diameters which are normal to a plane containing the axes of the lift pipes 12. The trays are located outside the approximate envelope of the rising streams of contact material, and are arranged to intercept the freely falling particles and to pass them stagewise from tray to tray until they reach the surface of the bed 15 in the lower region of the disengager.

The first, or uppermost, pair of tray segments 17 and 17', shown in Figs. 1, 2 and 3, are located in the upper region of the disengager at a level which is attained, for the most part, only by the smaller-size particles in the rising streams of contact material. As the completely decelerated particles become disengaged from the lift gas and gravitate toward the bottom of the disengager, those particles which are in the peripheral region of the vessel above the first tray segments are deposited thereon, while the centrally located particles pass downward between the first tray segments to be deposited at a lower level.

Tray 17 is provided with an arcuate dam or weir 21 which serves to retain on the surface of the tray a static accumulation of the particles deposited thereon. Additional particles slide downwardly over the surface of the static mass and pass over the dam into the arcuate space between the dam and the wall of the vessel, from which space the particles drain through openings 22 and fall freely to the peripheral region of the tray segment 18 next below.

Tray 17' is similar to tray 17, with the exception of the provision for drain. Instead of drain openings, such as 22, tray 17' is provided with a plurality of parallel downcomers 23, two being illustrated, which convey the particles as confined streams to tray segment 18' next below. The discharge ends of downcomers 23 are preferably located a short distance above the receiving tray.

The next lower pair of tray segments 18 and 18' are of similar shape, as shown in Figs. 1, 2 and 4, but extend inwardly a greater distance toward the central region of the disengager. Additionally, however, both tray segments have a plurality of parallel dams 24 forming spaced chords of the arcuate dams 21. Openings 22 in tray 18 permit the contact material to fall freely to tray 19 next below. Tray 18' is provided with a plurality of downcomers 25, two being shown, whose upper ends are disposed directly below the discharge ends of downcomers 23, and which converge so that their lower ends are at a single receiving location above the surface of tray 19'.

The next lower pair of tray segments 19 and 19', shown in Figs. 1, 2 and 5, have irregular inner edges, the edges being extended centrally to meet in a relatively narrow region at the center of the vessel, thus forming openings 26 of sufficient size to permit free passage of the separate rising streams of contact material. Trays 19 and 19' also are provided with arcuate dams 21 and with straight parallel dams 24. Openings 22 are provided along the entire peripheral annular space of tray 19, and at each end portion of the peripheral annular space of tray 19'. Tray 19' is provided with a single vertical downcomer 27

whose inlet end is located immediately beneath the aforementioned single receiving location.

Trays 20 and 20', shown in Figs. 1 and 6, are the lowermost trays. They project a relatively short distance inwardly from the vessel wall but extend circumferentially along the wall of the vessel a greater distance than any of the trays above. Trays 20 and 20' receive all the contact material falling freely through the openings 22 of trays 19 and 19'.

The slope and size of all the trays and the total flow area of the drains on each tray are such as to preclude, or at least minimize, any spill-over of contact material from the inner edges of the trays. Where the slope of the trays for any reason is not sufficient to assure freedom from spill-over, additional dams may be provided along the innermost edges of each tray.

By reason of the fact that the smaller particles tend to require a greater disengaging height than the larger particles, the concentration of small-size particles increases or, in other words, the average particle size decreases upwardly through the tray system.

Downcomers 23 therefore convey streams of contact material which have the highest concentration of small-size particles. Since the inlet ends of downcomers 25 are adjacent to and directly below the discharge ends of downcomers 23, the former will preferentially withdraw from the material on tray 18' that which has been received from tray 17'. Similarly, downcomer 27 preferentially withdraws from tray 19' that material which has been deposited thereon from downcomers 25.

Downcomer 27 is closed at its lower end, but has a side outlet adjacent thereto. From the lower end of the downcomer the contact material is passed into a conduit 28 through which the material is conveyed by gravity flow outwardly through the wall of the disengager to an elutriator, generally indicated by the numeral 29. Conduit 28 has a short vertical run 38 provided with an orifice plate 39 to control the flow of contact material to be elutriated.

The elutriator 29' comprises a hollow cylindrical member 32 having its lower portion depending concentrically within a closed cylindrical chamber 33 of substantially greater diameter. The lower end of conduit 28 extends into the upper region of cylindrical member 32 and is arranged to discharge the contact material axially downward therein. A distributor plate 34 is supported axially below the end of conduit 28 to intercept and distribute outwardly the falling stream of particles.

Elutriator gas is provided by withdrawing a portion of the disengaged lift gas from the disengager 11 through conduit 35. The inlet end of conduit 35 is located within the disengager at a point approximately level with the lowermost tray segment 20', and between the tray and the rising streams of contact material discharging from the lift pipes 12, such location being selected because the gas withdrawal does not interfere with the rise or fall of the contact material. To prevent the admission of stray particles of contact material into the conduit 35, the inlet end may be turned downward, as shown. The discharge end of conduit 35 is connected into the side wall of chamber 33 at a level substantially above the open lower end of cylindrical member 32, so that the elutriator gas will first travel downwardly within the annular passage formed between the concentric walls of members 33 and 75

32 and then flow upwardly into and through the latter, countercurrently to the falling stream of contact material.

The remaining portion of the lift gas is discharged from disengager 11 through overhead conduit 29, which is provided in known manner with a suitable damper, not shown, for the purpose of obtaining the desired proportion of gas flow to the elutriator 29'.

10 The elutriator separates the small-size particles from the large-size particles of contact material, the latter gravitating to the surface of a moving bed 36 of the same maintained at the bottom of chamber 33, and the former being carried upwardly out of the elutriator through conduit 37 by entrainment in the countercurrently flowing gas stream.

20 The separated large-size particles are continuously withdrawn from the bottom of bed 36 through conduit 38, provided with an orifice plate 39, and returned to the disengager 11. Conduit 38 introduces the elutriator stream of particles into the conical portion 14 at a low point within the compact moving bed 36.

25 In order to constantly maintain the compact moving bed 36 at the bottom of the elutriator, a by-pass conduit 40 withdraws a portion of the contact material flowing in the upper portion of vertical run 38 of conduit 28 at a point above the orifice 39 and passes the same downwardly to the surface of the bed 36. The discharge end of conduit 40 is below the lower end of cylindrical member 32, and determines the level of bed 36.

30 To assure that conduit 40 will by-pass a minimum of the small-size particles, the juncture of conduit 40 with vertical run 38 is preferably at the side directly opposite to the side at which the contact material enters the vertical run from the upper sloping portion of conduit 28. Thus, there is a minimum withdrawal of particles from that portion of the stream flowing through conduit 28 which contains the greatest concentration of fines. It is known that, by reason of the classification of particles which inherently occurs during flow along an inclined path, such as the upper 35 sloping portion of conduit 28, the small-size particles will flow in the vertical run along the wall portion which is nearest the direction of lateral admission.

35 Disengager gas outlet conduit 29 and elutriator gas outlet conduit 37 are preferably both connected to a common cyclone separator, not shown, for the removal of fine particles carried overhead from the disengager 11 and rejected fine particles discharged overhead from the elutriator 29'.

40 Referring to the modification of the invention illustrated in Figs. 7, 8 and 9, the disengager vessel 11 of Fig. 1, with slight modification of the internal tray structure, is provided with an internal elutriator, generally indicated by the numeral 51.

45 The internal elutriator 51 comprises an upright hollow cylindrical member 52 set in the tray segment 19' adjacent to the wall of the cylindrical portion 13. The lower end of cylinder 52 is open, and the upper end is closed by a horizontal end plate 53. End plate 53 has a central opening to receive the lower end of a gas outlet conduit 54. A portion of the separated lift gas within the disengager enters the lower end of cylinder 52 and is discharged from the upper end through conduit 54. End plate 53 also has four uniformly distributed openings, as shown in Fig. 8, to receive the lower ends of two pairs of downcomers 55 and 56. The pair of conduits 56 which have

their discharge ends located nearest the axis of the disengager have their inlet ends set in the tray segment 17', and the pair of conduits 56 whose discharge ends are farthest from the axis of the disengager have their inlet ends set in the tray segment 18'. The usual distributor plates 57 are placed below the discharge ends of the downcomers, as shown.

All the contact material drained from tray 17' is passed through conduits 55 to the elutriator, 10 and all the contact material drained from tray 18' is conveyed to the elutriator through downcomers 56. If desired, however, one or more openings 22 may additionally be provided in tray segment 18' in either of the embodiments of Figs. 1 and 7.

From the downcomers 55 and 56 the contact material gravitates freely through cylinder 52, countercurrently to the stream of lift gas moving toward the discharge conduit 54. The small-size particles of contact material are carried out of the vessel by entrainment in the discharging gas stream, and the large size particles descend by free fall to the surface of tray segment 58. Tray segment 58, shown in Fig. 9, is substituted for tray segment 20' of Fig. 1, and extends inwardly 20 toward the axis of the disengager sufficiently to intercept all the contact material discharging from the lower end of cylinder 52. Tray 58 also is provided with openings 22 through which the contact material drains to the surface of the bed maintained in the lower end of the disengager. A drain conduit 59, controlled by valve 60 is provided at the lower level of tray 58 in order that samples may be withdrawn, as desired.

In the present modification, the gas flowing through the elutriator is controlled in the same manner as it is controlled in the embodiment of Fig. 1. Gas discharge conduits 29 and 54 are connected to a common cyclone separator, not shown, for the removal of fines and other rejected particles.

Fig. 10 shows the application of the invention to a system in which surge capacity, in the form of a compact moving bed, is not provided within the disengager vessel, and the contact material slides freely through a disengager draw-off conduit to a compact moving bed located at a lower level along the down-flow path. Examples of such arrangement may be found in systems employing a separate surge hopper at the upper end of the conversion unit, and in a split kiln arrangement wherein the reactor is placed between upper and lower kilns, as shown in my companion application, Serial No. 285,270 filed April 30, 1952.

In Fig. 10, the elutriator 61 is located externally of the disengager 62. A tray structure, diagrammatically shown in broken lines, is provided within the disengager 62, and the elutriator feed stream of contact material is withdrawn from a tray having a high concentration of small-size particles, such as the upper or the middle trays. The elutriator feed stream is conveyed through conduit 63, provided with an orifice 64, into the elutriator 61.

The elutriator is located axially above a vessel 65 which may be a reactor storage hopper or may be the upper kiln of a split-kiln system such as that disclosed in my aforementioned companion case. Axially above the elutriator is a cyclone separator 66 which receives the lift gas discharge from the disengager through conduit 67, as well as the elutriator gas discharge through conduit 68.

The gas feed to the elutriator 61 through conduit 69 may be supplied from any suitable source,

such as the lift engager or the kiln. With a split-kiln system, as above-defined, the elutriator gas stream may be conveniently supplied directly from the upper kiln, a portion of such gas being by-passed to the elutriator for this purpose.

With the axial alignment of equipment, as shown, the elutriator conveniently discharges the returnable contact material vertically downward into the down-flow path of the circulatory system.

Obviously many modifications and variations of the invention as hereinbefore set forth may be made without departing from the spirit and scope thereof, and therefore only such limitations should be imposed as are indicated in the appended claims.

What is claimed is:

1. In a circulatory system for conveying granular contact material wherein said material flows compactly downward through at least one contact zone and is thereafter pneumatically elevated through one or more lift paths for recirculation, with consequent production of fines by attrition of said granular material, the method which comprises discharging said pneumatically elevated granular material upwardly within an elongated disengaging zone, said zone being of sufficient height to effect the disengagement of said granular material from the lift gas by gravitational deceleration and free fall of the granular material, intercepting the freely falling material at one or more levels within said disengaging zone located laterally of the discharged stream of granular material and lift gas, passing a portion of said intercepted granular material by free fall stagewise through said levels to the lower region of said disengaging zone, passing the remaining portion of said intercepted granular material along at least one confined path downwardly from at least one of said levels to an elutriating zone, said remaining portion having a relatively high concentration of said fines, separating the fines from the large-size particles of granular material within said elutriating zone by countercurrent engagement with a stream of gas, removing said fines from said circulatory system, and returning said large-size particles to said granular material flowing compactly downward.

2. The method as defined in claim 1 characterized in that said gas introduced into said elutriating zone comprises gas disengaged from said granular material within said disengaging zone, and said large-size particles of granular material discharged from said elutriating zone are returned to said compactly flowing material within the lower region of said disengaging zone.

3. The method as defined in claim 2 further characterized in that said small-size particles are removed from said elutriating zone by said stream of gas, and in that the remaining portion of the disengaged lift gas and said stream of gas from said elutriating zone are conveyed to a common separator for removing all the small-size particles of granular material from said gas.

4. A method as defined in claim 1 in which said disengaged granular material is intercepted within said disengaging zone at a plurality of vertically-spaced levels arranged to intercept material of different average particle size, decreasing progressively upward, and in which a portion of the granular material intercepted at one or more uppermost levels is conveyed stagewise along separate confined paths from level to level and subsequently withdrawn as a confined stream from said disengaging zone at a lower

level, said separate confined paths being arranged so that the discharge of granular material from the confined paths at one level is directly above the inlet to the confined paths at the next lower level.

5. A method as defined in claim 1 in which said elutriating zone comprises a confined zone within said disengaging zone and in open communication therewith only at the lower end of said elutriating zone, and wherein granular material is intercepted at one or more levels above said elutriating zone, said intercepted material being conveyed from each of said one or more levels along separate confined paths and discharged directly into the upper region of said elutriating zone, the disengaged gas being passed, in part, from the lower region of said disengaging zone upwardly into the open lower end of said elutriating zone and, in part, being discharged from the upper region of said disengaging zone, the gas and entrained solids being discharged from the upper end of said elutriating zone and passed with said lift gas discharged from the upper region of said disengaging zone to a common separator for removal from the combined gas stream of substantially all the small-size particles of granular material.

6. In a circulatory system for conveying granular contact material wherein said material flows compactly downward through at least one contact zone and is thereafter pneumatically elevated through one or more lift paths for recirculation, with consequent production of fines by attrition of said granular material, the method which comprises discharging said pneumatically elevated granular material upwardly within an elongated disengaging zone, said zone being of sufficient height to effect the disengagement of said granular material from the lift gas by gravitational deceleration and free fall of the granular material, intercepting the freely falling material at one or more levels within said disengaging zone located laterally of the discharged stream of granular material and lift gas, at least one of said levels being located in a region of said disengaging zone wherein the disengaged material predominantly comprises said fines, passing a portion of said intercepted material by free fall stagewise through said levels to the lower region of said disengaging zone and thence to the surface of said compactly flowing material, passing the remaining portion of said intercepted material, predominantly comprising fines, to an elutriating zone, separating the fines from the large-size particles of granular material within said elutriating zone, and retaining said large-size particles to said compactly flowing granular material.

7. In a circulatory system for granular material wherein said material gravitates as a compact moving column along a down-flow path and is thereafter elevated by means of lift gas through one or more lift pipes, with consequent attrition of said granular material such as to require removal from said system of small-size attrited particles, the combination of a disengaging chamber containing the upper end portion of at least one of said lift pipes, said disengaging chamber extending above the discharge end of said lift pipe a distance sufficient to permit substantially complete gravitational deceleration of granular material discharged from said lift pipe, and having an upper outlet for disengaged lift gas and a lower outlet for disengaged

granular material, one or more trays attached to the side of said disengaging chamber above said discharge end of said lift pipe and adapted to intercept freely falling granular material, at least one of said trays being located in the upper region of disengagement to thereby intercept a portion of the disengaged granular material having a relatively high concentration of small-size particles, an elutriating chamber having contact material and elutriating gas inlets, and having an outlet for large-size particles of granular material and an outlet for said elutriating gas and entrained small-size particles of granular material, and means for passing said portion of intercepted granular material having a relatively high concentration of small-size particles to said elutriating chamber.

8. Apparatus as defined in claim 7 including a cyclone separator, and means for conveying thereto both the disengaged lift gas from said disengaging zone and the mixture of elutriating gas and entrained small-size particles from said elutriating zone.

9. Apparatus as defined in claim 7 in which said trays are four in number and are attached to the sides of said disengaging chamber at longitudinally spaced levels above said discharge end of said lift pipe, and including downcomers in at least the two uppermost trays for conveying the concentrate of small-size particles from said uppermost trays to said elutriating chamber.

10. Apparatus as defined in claim 9 in which the third tray from the top extends transversely across the disengaging zone and has one or more openings adapted to freely pass the streams of contact material discharging upwardly from said one or more lift pipes, said third tray having set therein a withdrawal conduit which, together with said downcomers comprises said means for passing said small-size particles to said elutriating chamber.

11. Apparatus as defined in claim 10 in which each of said trays comprises a pair of diametrically opposite inclined segments whose inner edges are just outside the stream profile of said discharging stream of granular material, and in which the segments of said third tray are joined along a portion of their inner edges.

12. Apparatus as defined in claim 7 in which said trays are four in number and are attached to the sides of said disengaging chamber at longitudinally spaced levels above said discharge end of said lift pipe, and in which said elutriating chamber comprises a hollow cylindrical vessel set in the third tray from the top, said elutriator being closed at its top and open at its bottom, and including at least one downcomer set in each of the first and second trays and extending downwardly into said elutriator.
